BUFF SECTION MANUFACTURE

Frederick H. Thompson, Fremont, Ohio, assignor
to The Yerges Manufacturing Company, Fremont, Ohio, a corporation of Ohio

Application October 1, 1951, Serial No. 249,077

2 Claims. (Cl. 51—193)

1

This invention relates to the manufacture of buffing disks comprising the assembly into sections of similar sheet portions of fabric.

This invention has utility when incorporated in radially extending units or sections of axially collapsed circular elements or sheets of warp and woof material in exposing bias or major non-fraying peripheral face with taper depth single ply pockets or fluting for composition holding and divergently puckered for efficient ventilation in operation.

Referring to the drawings:

Fig. 1 is a side elevation of a fabric element circular sheet;

Fig. 2 shows axial thrust collapse stage for the element of Fig. 1;

Fig. 3 is a side elevation of an assembled collapsed element as the basis for a radial unit;

Fig. 4 is a plan view of an assembly plate with spacing pins for radial grouping thereon of assembly units of Fig. 3;

Fig. 5 is a side elevation, partly folded back, of an adhesive face disk of quick drying property or characteristic;

Fig. 6 is a fragmentary plan view of the radial unit assembly of Fig. 4 with central bonding effective from the disk of Fig. 5;

Fig. 7 is a fabric facing disk of minor dimension relatively to the element of Fig. 1, desirably of more heavy fabric and at least of as great diameter as the disk of Fig. 5;

Fig. 8 is a portion in plan, showing the concealing of the adhesive carrying disk by the fabric disk of Fig. 7 on the radial unit assembly;

Fig. 9 is a broken away portion showing tensioned thread spiral stitching assembling over both sides of the central region of the converging units of the facing disks;

Fig. 10 is a body-providing reinforcement cardboard type disk;

Fig. 11 is a partly broken away side elevation of the unit assembly in which the spiral stitching is coated with an additional bonding agent in the assembly of Fig. 10 disks therewith; and

Fig. 12 is a side view of the completed buff section.

The body or base hereunder as adopted for flexibility range of fitting into wide uses is cotton warp and woof material, preferably a canvas which may vary in thread per inch of 48—48, or even in greater fineness or closeness 80—92. The fineness of the threads in this weave materially reduces the tangential extent of fraying at the 90° apart portions of the circular sheet periphery. For 16" diameter buff body, a practice

2

adopted is to build up from circular sections of elements 1 of the selected material. In carrying thru, it is convenient to have the center of such elements 1, with a center identification marking or small opening 2.

The elements 1 are formed into units by thrusting a rod or stem 3 to carry the marking 2 thru a sleeve 4, an aligned adjacent ring 5 and into a short cylindrical paper or adhesive face tube 6, for the rod 3 to protrude slightly beyond the tube 6. The rod 3 is then withdrawn from the collapsed element to be held in a unit 7 with its tip but slightly thru the tube 6 and the ring 5 inward sufficiently from the larger end of the unit as not to be readily slipped therefrom. The collapsing forms single ply fluting developed progressively as away from the tube 6. The outer side of the single ply sheet shows the fluting radial and thus diverging in the outwardly-widening taper of the centrally collapsed sheet.

Grouping of the units is on a rigid circular base 8 having a central marking or port 9. Thereabout and slightly inward from the periphery is an endless annular series of partitions or pins 10. Besides the flexibility to be reached in the ultimate product from the different characters of weave in the elements 1, the number of the partitions or pins 10 has been varied in practice, say from twenty-five to thirty-two. Even with the same character elements 1, when in the collapsed unit, its form responds to a flattening out or sector in the assembly for symmetry of fabric continuity thruout the full annular extent. In this grouping, the almost insignificant tubes 6 are in proximity to the port 9.

The assembly is effected by placing an adhesive face 11 of a thin paper or the like disk 12 to have its central marking 13 in register with the port 9.

A cover disk 14, say of heavier stock, such as duck, may have its central marking 15 in register with the marking 13 of the disk 12. The disk 14 may be of just larger diameter than the disk 12. While the diameter of these disks 12, 14, may be according to the work-down area predetermined for the completed buff body. For an area of inward working on a 16" diameter disk, the disk 14 may be 8". The adhesive 11 and its disk 12 permit orienting of the base 8 for the reverse central region to have a disk 12 and then a disk 14 placed thereon, instead of having such initially on the base 8. The radial grouping of the units 7 is now clear of the partitions 10 and the rings 5 may be now slipped clear of the units 7. About the marking 15, spiral stitching 16 (Fig. 9) contributes to major anchoring of

the assembly, for at say 25# tension on the thread, there is a tightness giving compactness or firmness to the buff section central body in which the spacing between the pitches of the spiral may be $\frac{1}{4}$ ", $\frac{3}{8}$ ", or such other selection as may meet the particular job in trade for which it is to be used.

The disk 14 determines the area for the spiral stitching 16. Water glass or other binding medium or cement 17 may be coated thereon as an adhesive for cardboard or fiber rigid disk 18 having a central marking 18' (Fig. 10). With the adhesive 17 mounting a facing disk 18 on each side, grouping stage 19 may be given a peripheral trim 20 and concentric therewith an opening 21 in forming a completed buff element 22 (Fig. 12), in which radial pockets 23 are of gradually decreasing cross section as extending inward from bias or major non-fraying trim 20. The outside-the-pockets flutings 24 as in and between the elements 7 provide effective fan vane-like performance in promoting self ventilation, whether the operation speed be in the range of 10,000 lineal feet per minute or 850 lineal feet per minute. The shaft receiving opening 21 may be such as to remove the tubes 6.

General rigidity for the section 22 is had from the thickness adopted for the facing disks 18, adopted as cardboard, say $\frac{1}{8}$ " stock. However, in practice such may vary. Use has been of $\frac{1}{16}$ " and up to $\frac{1}{4}$ " thickness cardboard. In the buff ring assembly of the section on a shaft or arbor between clamping disks, the thickness adopted for the disks as abutting establishes a looseness or openness for ventilation of the fan-vanelike-providing flutings 24. There are two factors of practical importance due to the fluting. One is the axial compactness of the several sections 22 grouped on the shaft, and the other is in the build-up of the section 22 as to the number of radial units 7. There is ventilation enhancement value in the lack of symmetry developed from the central thrust on the elements 1 to form the units 7. Such irregularities in the flutings or pocket sides 24 develops a variance in the actual number of plies taken parallel to the shaft thru each unit. However, as a mean or average, such works out for consideration of a section having twenty-five radial units 7 as a 25 ply section, and likewise for thirty-two units in a section to be the practical equivalent of 32 ply section. Actually in practice there is very much improved working efficiency over such number of separate or independent plies due here to the fluting or return-bends and their reinforcement or hold-up values as in the warp and woof stock itself, for in the preferred form as herein disclosed, radially outward from the spiral stitching 16, no extra threads are in the section 22. The flutings or puckers 24 as narrow readily hold the compound

or composition for acting upon the work, with resulting increase in speed for efficient performance at the lineal peripheral speed of the buff. According to the inter-section spacing, there may be section assembly yield for pushing work into the rotating buff. For more hard or rigid buffing, the facing disks 18 may be removed and the spiral stitched central body or core region worn down to the extent operation economies may take into account.

What is claimed and it is desired to secure by Letters Patent is:

1. A method of manufacturing a buffing wheel from a plurality of single ply fabric disk sheets, comprising: separately pushing the center of each sheet through a tubular element to form each sheet into an irregularly fluted conical member of fabric with the apex at the center of each sheet, radially arranging said conical members in a common plane in a circle with their apices adjacent each other to form a circular disk of said members, placing said disk of members between a pair of flat adhesive coated disks to maintain the radial location and relative position of said members in said plane, and then stitching said flat disks to each of said members whereby the center of said flat disks adjacent the apices of said members forms the axis of said buffing wheel.

2. A buffing wheel section consisting of a plurality of similar radially diverging conical members, each of said members being collapsed from a single ply disk of fabric into a conical shape with fluted sides and with the center at the apex of each member, said members being arranged radially in a plane with their apices adjacent each other to form a circular disk so that said apices are all adjacent the axis of said buffing wheel section, and so that all points on the peripheries of all the disks are equally spaced from the axis of said section, a pair of flat disks on opposite sides of said members and covering said apices, and means for fastening each of said members to said flat disks to maintain their relative location in said buffing wheel section.
